UNITED STATES PATENT OFFICE.

LLOYD M. BURGHART, OF GOVANS, MARYLAND, ASSIGNOR TO U. S. INDUSTRIAL
ALCOHOL CO., A CORPORATION OF WEST VIRGINIA.

PROCESS OF RECOVERING VOLATILE ORGANIC ACIDS FROM DISTILLERY WASTE.

1,426,457.

Specification of Letters Patent. Patented Aug. 22, 1922.

Application filed June 24, 1918. Serial No. 241,502.

To all whom it may concern:

Be it known that I, LLOYD M. BURGHART, of Govans, in the county of Baltimore, and in the State of Maryland, have invented a certain new and useful Improvement in Processes of Recovering Volatile Organic Acids from Distillery Waste, and do hereby declare that the following is a full, clear, and exact description thereof.

10 My invention relates particularly to a process for treating the waste obtained from distilleries in the production of alcohol.

15 The object of my invention is particularly to utilize the waste obtained from the distillation of various materials used in the production of ethyl alcohol.

20 More particularly, the object of my invention is to make use of the waste materials obtained in the production of ethyl alcohol from sugary materials such as molasses, which may, for example, be obtained in the manufacture of cane or beet sugar, or from potatoes, or grain, such as wheat, rye, barley, corn, etc.

25 The object of my invention is, furthermore, to provide a process by means of which the esters of volatile organic acids, and particularly of the volatile acids of the aliphatic series, may be readily obtained and 30 without the application of high temperatures in the distillation thereof, as herein-after referred to.

35 Further objects of my invention will appear from the detailed description thereof contained hereinafter.

While my invention is capable of being carried out in many different ways, for the purpose of illustration I shall describe only one way of carrying out the same herein; 40 and while my invention is capable of being carried out in connection with many different types of apparatus, I shall describe only one type of apparatus which may be used in connection therewith in the accompanying drawings, in which—

Figure 1 is a diagrammatic representation of an apparatus which may be used in connection with my invention; and

45 Figure 2 is an end elevation of a type of car used in connection with the same.

In the drawings, I have shown two preliminary mixing tanks 1, having a plurality of stirrer arms 2, adapted to be rotated in any suitable manner, said tanks 1 being pro-

vided for mixing a soluble caustic such a 55 caustic soda with a quantity of the magma, which may be evaporated distillery waste or slop, and which may have a density of 25° Bé. or higher.

From the mixing tanks 1, the material 60 may be conveyed into a plurality of pans 3 on trucks 4, containing racks 5 to receive the same, which trucks may be arranged to run upon a track 7 into a furnace chamber 8. The material in the pans 3 becomes dried in 65 this manner to form a "clinker." This clinker contains sodium oxalate, as well as sodium salts of a number of volatile acids, such as formic, acetic, butyric acids, etc. The clinker may be then removed from the 70 pans and introduced into a plurality of wooden tanks 9. These tanks 9 may be supplied with a quantity of water and sulphuric acid, and the contents of said tanks may be heated by means of live steam fed into the 75 same by means of a pipe 10, having branch pipes 11, leading into the same. Said steam pipes 11 may have a pipe 12 connected thereto to supply compressed air, in order to assist in the agitation of the materials contained in the tanks. The sulphuric acid is added to neutralize the excess alkali, as neutralization is found to aid in the subsequent filtration. Thereafter a quantity of lime is added sufficient to precipitate the oxalic acid 80 as calcium oxalate. The liquids may be then transferred from the tanks 9 to a filter 13. The filtrate from the filter 13, which contains the sodium salts of the volatile acids above referred to, may be evaporated to 85 dryness, or nearly so, and may be then treated in a still 14, which may have a heating jacket 15, an inlet for live steam 15^a and a refluxing column 16^a with a nonvolatile mineral acid such as sulphuric acid in excess of 90 that required to liberate the volatile acids and with a quantity of methyl alcohol, said still preferably having a vapor outlet pipe 17, leading to a condenser 18, which may be provided with an outlet pipe 19, leading to 100 a receiving tank 20, connected by pipe 21 to a vacuum pump 22. In the employment of the foregoing apparatus the crude esters of the volatile acids collect in the tank 20 and may be drawn off therefrom by a pipe 23 and 105 conveyed by the same to a column still 24, which may have an inlet 24^a for live steam and a vapor outlet pipe 25 leading to a con-

denser 26. From the condenser 26, the esters may be drawn off into a plurality of receiving tanks 27, 28, 29.

As a specific example of my invention, I may proceed as follows: A quantity of the distillery waste or slop, after having had the alcohol removed therefrom, is evaporated in the usual way to form a magma, which may have a density of 25° Bé. or higher. This magma may be mixed in the proportion of three parts by weight of magma to one part by weight of caustic soda in the tanks 2, until the alkali has become completely dissolved. If desired, the two tanks 2 may be operated alternately, so that, while one tank is being charged, the other is being discharged. The mixture thus obtained may be transferred to the pans 3 on the trucks 4 and is introduced into the furnace chamber 8, where the material may be subjected to a temperature of from 175° to 250° C. for 8 to 24 hours, the time of treatment being varied according to the temperature. Where the temperature is low, the treatment is for a longer period of time than where the temperature is higher. When the reaction is complete, the treatment in the furnace chamber 8 is discontinued. The effect of the treatment in the furnace chamber 8 is principally to bring about the production of volatile organic acids as well as oxalic acid. The clinker thus obtained, and which contains a quantity of sodium oxalate amounting to approximately 10% of the weight of the clinker, and a quantity of sodium salts of a number of volatile acids, such as formic, acetic, butyric acids, etc., amounting to from 12% to 20% of the weight of the clinker, may be treated with, for example sulphuric acid in the proportions of one part by weight of clinker, two parts by weight of water, and one-third part by weight of sulphuric acid of 66° Bé. in the tanks 9. The amount of sulphuric acid that is intended to be used is sufficient merely to neutralize the alkali and not to liberate the oxalic acid and volatile acids from their sodium salts. During the treatment with the sulphuric acid, heat may be applied by the injection of live steam through the pipe 10, together with compressed air through the pipe 12, if desired. Then a sufficient quantity of lime, or the like, may be added to precipitate the oxalic acid as calcium oxalate. The amount of lime added will usually be about 5% of the weight of the clinker introduced into the tanks 9. The calcium oxalate and other solid materials present are then separated from the liquids by means of the filter 13. The filtrate from this filter will contain the sodium salts of the volatile acids above referred to. The filtrate may be then evaporated to dryness, or nearly so. The solid materials are then introduced into the still 14, and a quantity of the same, amounting to 200

pounds, is treated therein with 80 pounds of concentrated sulphuric acid of 66° Bé. and 50 pounds of methyl alcohol. Instead of the methyl alcohol, however, ethyl or amyl alcohol may be used, but I prefer to use methyl alcohol, as thereby the temperatures of distillation used in distilling the esters of the volatile organic acids may be kept at a very low point. The materials in the still 14 may be then heated for some 3 hours, while using the refluxing column 16, at a temperature of for example 20-25° C., and thereafter the methyl esters of the volatile organic acids may be allowed to distill over through the tube 17, after which they may be condensed in the condenser 18 and received in the tank 20. From this point the methyl esters may be withdrawn for any desired purpose or may be purified and separated by treatment in the column still 24, from which the products produced may be condensed in the condenser 26 and received in the receiving tanks 27, 28, 29.

In this way the methyl esters of formic, acetic and butyric acids may be obtained, and thereafter, if desired, the formic, acetic and butyric acids may be obtained in any desired manner, as for example by treating each of the methyl esters by adding thereto an excess of caustic alkali to saponify the same, distilling off the methyl alcohol, evaporating to recover the dry salt, treating with an excess of concentrated sulphuric acid to liberate the corresponding acid and recovering the latter by distillation.

While I have described my invention above in detail, I wish it to be understood that many changes may be made therein without departing from the spirit of my invention. For example, instead of calcium compounds, I may use salts of the other alkaline earth metals, and I wish this to be understood wherever I have referred to the use of calcium compounds; and instead of caustic soda, I may use other alkalies or carbonates of the alkali metals or mixtures of the same.

I claim:

1. The process which comprises mixing a soluble caustic with a quantity of sugary materials, exposing the mixture to furnace heat sufficient to form a clinker comprising a corresponding soluble oxalate, dissolving this oxalate and associated salts in acidified water, separating solids from the solution so formed, thereafter adding to the filtrate lime sufficient to precipitate calcium oxalate, separating the precipitate from the liquid portion, evaporating the liquid portion, and thereafter treating it with an excess of a non-volatile mineral acid and with an alcohol while collecting the esters evolved therefrom under reduced pressure.

2. The process which comprises mixing a soluble caustic with a quantity of sugary ma-

terials, exposing the mixture to furnace heat sufficient to form a clinker comprising a corresponding soluble oxalate, dissolving this oxalate and associated salts in acidified 5 water, separating solids from the solution so formed, thereafter adding to the filtrate lime sufficient to precipitate calcium oxalate, separating the precipitate from the liquid portion, evaporating the liquid portion, and

thereafter treating it with an excess of a non-volatile mineral acid and with an alcohol while collecting the esters evolved therefrom. 10

In testimony that I claim the foregoing I have hereunto set my hand.

LLOYD M. BURGHART.
